Attorney
G. A.

UNITED STATES PATENT OFFICE

JOHN PATRICK MOHEN, OF ST. LOUIS, MISSOURI

DISPLAY CARTON

Application filed June 3, 1927. Serial No. 196,190.

This invention relates to display cartons for the packing, shipping and display of merchandise in general, and particularly for the handling of candies, confectionery or any small stuff where it may be desirable to make a counter display of the goods for sale.

The primary object of the invention is to provide a carton of fibre board, pasteboard or any other suitably flexible material, where-
10 in is incorporated a collapsible and extensi-
ble element made of the same sort of material, which element may be folded down or col-
lapsed upon the contents of the carton, so as
15 to form a sort of cover for the goods in ship-
ment or storage, and which may be readily
expanded into the form of a stepped series
20 of shelves for the display of the goods con-
tained within the carton.

Another object is to provide a shipping
25 carton for merchandise, whereby the goods
may be packed and shipped in the usual com-
pact form, the said carton, however, having
an extensible element for the display of the
same goods upon a counter.

30 A further object is to provide a blank of
flexible material adapted to form an insert,
including integrally connected central and
wing portions, the central portion being suit-
ably stamped, formed, cut and scored for
35 forming a series of collapsible and extensible,
stepped shelves for supporting and display-
ing merchandise, and the wing portions being
correspondingly cut to form lateral support-
ing elements for the central portion and the
40 stepped shelves thereof when expanded.

In the drawing—

Figure 1 is a perspective view of a carton
45 equipped with this invention, the stepped in-
sert being shown in erected or expanded posi-
tion;

Figure 2 is a similar perspective view, the
50 said stepped insert being shown in collapsed
position;

Figure 3 is a plan view of a blank of fibre
55 board, the same being properly scored or
stamped for forming the middle, stepped sec-
tion of the said insert, and the two integrally
connected side supporting wings of the said
insert;

50 Figure 4 is a side elevation of an insert

element for any conventional form of flat rec-
tangular carton, this said element being the
essence of my invention, and being shown in
this figure in expanded form:

Figure 5 is a plan view of the insert ele- 55
ment in expanded form.

In carrying out this invention, I provide a
blank 1 of any suitably flexible material, such
as fibre-board, strawboard, pasteboard or
sheet metal, and cut, score and mark the same 60
for forming the central, stepped section 2
of the said insert, and the two integrally
connected, side supporting wings 3. Upon
the said central portion 2, I score or mark a
plurality of transverse, parallel and prop- 65
erly spaced flexure lines 4, thereby defining a
head piece 5, a tail piece 6 and intermediate,
stepped shelf portions 7, which are adapted
to be erected or expanded one above the other
and held in that relation at their front edges 70
by the riser portions 8. Brace tab portions
16 are also cut partly free from the head
piece 5, on the lines 17 parallel with the edges
12 of the central portion 2. Correspondingly
the wing portions 3 are cut to form the 75
stepped, shelf supporting bearings 9, the
riser abutments 10 and the backwardly ex-
tending brace portions 18. Wing flexure
lines 11 slightly inset with relation to the
adjacent parallel edges 12 of the central por- 80
tion 2 of the blank 1, serve to demarcate the said
integrally connected portions 2 and 3. The
blank as thus formed and prepared may be
attached to any conventional form of carton
13, by fastening the tail piece 6 to the inner 85
face of one end of the carton, as shown at 14.

In use the insert may be readily folded
down in flat form upon the goods in the car-
ton, by turning the wing portions 3 up under-
neath the central portion 2. The usual cover
90 (not shown) may then be placed upon the
carton, and the carton is then ready for ship-
ment or storage. An attractive counter dis-
play of the goods is readily made by simply
expanding the shelves 7, turning down the
95 side wings 3 within the sides of the carton and
adjusting the shelves 7 properly upon the
bearings 9 of the wings 3. The braces 18
abutting against an end of the carton, serve
100 to prevent the expanded insert from acci-

dentally collapsing; and the brace tabs 16, being bent backwardly at their free ends and having those ends set upon the upper edges of the braces 18, serve to maintain the head piece 5 in its vertical position. Any desired advertising may be printed upon the head piece 5.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. A display insert for a carton consisting of a blank of flexible material, the same comprising a central portion forming a series of hingedly connected extensible and collapsible stepped shelves, and side supports integrally connected directly to the side edges of the stepped shelves and arranged to swing laterally to a position directly beneath the stepped shelves, whereby when the display insert is set up it will be closed at the top, front and sides and open at the back and bottom to enable it to be placed within the carton over the contents thereof, the open back affording access to the contents of the carton.

2. A display insert for a carton constructed of flexible material and consisting of a series of stepped shelves hingedly connected so as to collapse, and stepped side supports located wholly beneath the shelves and hinged at the top directly to the side edges of the stepped shelves so as to swing laterally with respect thereto, the said insert when set up being open at the bottom and back to enable it to be placed within a carton over the contents thereof and being closed at the top, sides and front to protect the contents, the open back affording access to the contents of the said carton.

In testimony whereof I affix my signature.
JOHN P. MOHEN.
